UNITED STATES PATENT OFFICE

JACK I. LONDON, OF NEW YORK, N. Y.

DESIGN FOR AN EMBLEM STAND

Application filed January 29, 1931. Serial No. 38,480. Term of patent 7 years.

To all whom it may concern:

Be it known that I, JACK I. LONDON, a citizen of the United States, and resident of the borough of Bronx, city of New York, in the county of Bronx and State of New York, have invented a certain new, original, and ornamental Design for an Emblem Stand, of which the following is a specification, reference being had to the accompanying drawings, forming part thereof.

In the drawings, Fig. 1 represents a front elevation of an emblem stand showing my new design and Fig. 2 shows an end view of Fig. 1.

The design shows a platform having decorated legs. A pair of decorated pillars on the platform support a frame, having a border decorated on its front side only. The center of the frame within the border is ornamented as shown in the drawings.

I claim:

The ornamental design for an emblem stand, as shown and described.

Signed at the borough of Manhattan, city of New York, in the county of New York and State of New York, this 26th day of January, A. D. 1931.

JACK I. LONDON.
